UNITED STATES PATENT OFFICE

PAUL H. SCHOPPEL, OF NEW YORK, N. Y.

DESIGN FOR A BOTTLE OR THE LIKE

Application filed May 17, 1933. Serial No. 48,154. Term of patent 3½ years.

To all whom it may concern:

Be it known that I, PAUL H. SCHOPPEL, a citizen of the United States, residing in the borough of Manhattan, city of New York, county of New York, and State of New York, have invented a new, original, and ornamental Design for a Bottle or the like, of which the following is a specification, reference being had to the accompanying drawing, forming part thereof.

In the drawing:

I claim:

The ornamental design for a bottle or the like, as shown.

PAUL H. SCHOPPEL.
